RAILWAY SPIKE

Jakob Hojnowski, Nekoosa, Wis.

Application July 25, 1938, Serial No. 221,247

3 Claims. (Cl. 85—23)

This invention relates to certain new and useful improvements in railway spikes.

The primary object of the invention is to provide a railway spike for anchoring the rail to a wooden tie in which a locking key is associated with the spike and tie for holding the spike against movement relative to the tie with the flanged head of the spike in engagement with the base flange of a rail for holding the latter on the tie.

10 A further object of the invention is to provide a railway spike of the foregoing character that has a locking key for holding the same anchored to a tie slidably and interlockingly engaged therewith, the locking key having a laterally extended blade that projects laterally of the spike and into the wooden tie to assume an arcuate position substantially transversely of the longitudinal axis of the spike to prevent accidental removal of the spike from the tie.

15 20 With the above and other objects in view that will become apparent as the nature of the invention is better understood, the same consists in the novel form, combination and arrangement of parts hereinafter more fully described, shown in 25 the accompanying drawing and claimed.

In the drawing:—

Figure 1 is a side elevational view of a spike constructed in accordance with the present invention and associated with a rail and tie that 30 are fragmentarily illustrated in section, the locking key associated with the spike and tie also being shown in section;

Figure 2 is a rear elevational view of the spike and locking key with the rail fragmentarily illustrated in elevation and the supporting tie in section, the locking key extending through a groove for a portion of its length, at one side edge of the spike;

Figure 3 is a view similar to Figure 2 with the 40 groove in the spike for the sliding reception of the locking key disposed at an angle to the longitudinal axis of the spike;

Figure 4 is a detail sectional view taken on line 4—4 of Figure 2, showing the locking key to be of 45 triangular formation in cross section with a blade portion of the key projecting laterally of the spike;

Figure 5 is a perspective view of the locking key;

Figure 6 is a perspective view of another form of 50 spike having a modified form of cross groove for the passage of the lower end of the locking key; and

Figure 7 is a perspective view of another form of spike having a locking key associated therewith.

55 Referring more in detail to the accompanying

drawing and particularly to Figures 1, 2, 4 and 5, the reference character 10 designates a wooden railroad tie with a rail having a base flange 11 supported thereon and anchored in position by means of a spike that has its shank 12 driven into the wooden tie and having an offset flanged head 13 overlying and engaging the base flange 11 of the rail.

The shank 12 of the spike as shown in Figures 2 and 4 has a groove 14 formed therein at a rear longitudinal corner edge thereof from a point substantially midway the ends of the shank through the head 13 thereof, the side wall 15 of the groove 14 as shown in Figure 4 being disposed at an acute angle to the base wall of the groove. 15 An arcuate groove 16 extends substantially transversely of the shank 12 at the rear side thereof with one end of the arcuate groove communicating with the lower end of the longitudinal groove 14. As shown in Figure 1 the opposite or upper 20 and lower walls 17 of the groove 16 converge toward the rear wall of the shank to form a locking groove.

A key is slidably and interlockingly received in the grooves of the shank for cooperation with 25 the tie 10 to lock the spike against accidental displacement, the key in its original form being shown in Figure 5 and designated by the reference character 18, the key being triangular in cross section as shown in Figure 4 to provide a 30 flat edge wall 19 with tapering sides 20 merging into a straight edge 21. The inner end of the key has an offset head 22 and a pointed end 23. A sharpened blade extension 24 projects from the 35 straight edge 21 of the key adjacent the pointed end 23 thereof.

To anchor the rail to the tie 10, the spike is first driven into the tie with the flanged head 13 of the spike engaged with the base flange 11 of the rail. The locking key 18 is then positioned 40 in the upper end of the groove 14 with the flat side wall 19 of the locking key engaged with the bottom wall of the groove 14 while one of the inclined sides 20 of the locking key engages the inclined side wall 13 of the groove 14. The key 45 is then driven downwardly into the tie 10 through the slot 14 in the shank 12, the pointed end 23 of the key 18 being directed into the adjacent end of the arcuate groove 16 in the shank with the key 18 ultimately assuming the position shown 50 in Figure 1 wherein the end 23 assumes an upwardly arched position shown at 23a in Figure 2. The blade extension 24 on the key projects laterally of the shank 12 of the spike and bites into the tie 10 to prevent upward movement of the 55

key and spike relative to the tie. The inclined or tapering sides of the blade 24 cooperate with the inclined sides 17 of the arcuate groove 16 in the shank of the spike to prevent lateral displacement 5 of the key relative to the shank and to form an interlocking connection between the key and shank as shown in Figure 1. The offset head 22 of the key 18 is disposed at the outer side of the spike head to facilitate gripping engagement 10 thereof for the forceful removal of the key, should it be desired to remove the spike from the tie.

In the form of invention shown in Figure 3, the groove 14a at the rear side of the shank 12 for the sliding reception of the key 18 is formed 15 at an angle to the longitudinal axis of the shank to increase locking engagement between the key and shank.

In the form of invention shown in Figure 6, the shank 12a of the spike has a substantially 20 transversely extending arcuate groove 16a at the rear side thereof and the top and bottom walls of the groove 16a are slotted or serrated as at 25 with the serrations in each wall driven into contact with each other from one side of the shank and at one end of the groove to provide a more 25 definite entrance into the groove for the end of a locking key.

The shank 12b of the spike shown in Figure 7 has a reduced lower end 12c forming opposite 30 pointed shoulders 26 that cooperate with the pointed end 27 of the shank to facilitate the driving of the spike into a tie, the shank 12b being provided with a rear corner edge groove 14b and an arcuate cross groove 16b for the reception of the key 18 as shown in Figures 1, 2, 4 and 5.

From the above detailed description of the invention, it is believed that the construction and use thereof will at once be understood, and while there are herein shown and described the preferred embodiments of the invention, it is nevertheless to be understood that minor changes may be made therein without departing from the spirit and scope of the invention as claimed.

I claim:—

1. In a railroad spike of the character described, a spike having a shank and an offset head, the shank of the spike having a groove in the rear wall thereof extending downwardly through the head and merging into an arcuate

groove extending across the shank at a point intermediate the upper and lower ends of the shank, in combination with a key for locking the spike in a wooden tie comprising a shank of the same cross-sectional shape as said groove with the free end of the key projecting through the arcuate groove at the other side of the shank, and a laterally extending blade carried by the key shank adapted to be moved into arcuate formation opposite the arcuate groove and projecting laterally of the spike for biting engagement in the tie. 5

2. In a railroad spike of the character described, a spike having a shank and an offset head, the shank of the spike having a groove in the rear 15 wall thereof extending downwardly through the head and merging into an arcuate groove extending across the shank at a point intermediate the upper and lower ends of the shank, in combination with a key for locking the spike in a wooden 20 tie comprising a shank of the same cross-sectional shape as said groove with the free end of the key projecting through the arcuate groove at the other side of the shank, and a laterally extending blade carried by the key shank adapted to be 25 moved into arcuate formation opposite the arcuate groove and projecting laterally of the spike for biting engagement in the tie, the arcuate groove having a flat bottom wall and converging side walls to form an interlocking connection with 30 the key.

3. In a railroad spike of the character described, a spike having a shank and an offset head, the shank of the spike having a groove in the rear 35 wall thereof extending downwardly through the head and merging into an arcuate groove extending across the shank at a point intermediate the upper and lower ends of the shank, in combination with a key for locking the spike in a wooden 40 tie comprising a shank of the same cross-sectional shape as said groove with the free end of the key projecting through the arcuate groove at the other side of the shank, the top and bottom walls of the arcuate groove being serrated with the serrations in each wall moved into engagement in one direction transversely of the shank to define an entrance opening for the entering end of the key. 45

JAKOB HOJNOWSKI.
